UNITED STATES PATENT OFFICE.

HARRY C. EUSTIS, OF LOS ANGELES, CALIFORNIA.

SNAP-ACTION VALVE FOR FLUSH TANKS AND THE LIKE.

Application filed May 8, 1926. Serial No. 107,682.

The present invention relates to ball cocks for flush tanks and to other automatic valves which are gradually moved to closed position by actuating means.

In devices of this class an objectionable feature resides in their tendency to "chatter" as the valve is nearing closed position. Such chattering is apparently due to the fact that the valve, when very close to closed position, is thrown forcibly to its seat by passing fluid and when the flow of fluid is stopped by closing of the valve the latter rebounds from its seat and the operation is again repeated. Such cycle of movements on the part of the valve is repeated several times per second, resulting in objectionable noises.

Another cause for such noise is that of the "wire-drawing" of the fluid through a very small opening between the valve and its seat. In the case of usual float controlled valves, the float rises slowly and steadily, positively moving the valve to closed position but never allowing it to close except gradually.

One of the principal objects of the invention is to provide a valve of the class described, on which the valve proper, when in close proximity to the seat, is caused to be moved suddenly to the seat without tendency to rebound.

Another important object of the invention is to provide a device of the class described in which the valve is retarded at all times so that sudden movement or frequent reversal of movement is prevented.

Another object of the invention is to provide a simple and substantial device of the class described, with a view to eliminating spring actuated automatic parts and the like.

Still other objects and advantages of my invention will appear hereinafter.

In the accompanying drawings I have shown my invention applied to flush tanks, although it is conceived that my invention is applicable to any automatic valve which ordinarily is positively but slowly moved to closed position.

In the said drawings:

Figure 1 is a view in vertical section of a flush tank to which the said embodiment of my invention is applied.

Figure 2 is a vertical section of the said embodiment.

Figure 3 is a view in section of the lower part of said embodiment.

More specifically, the numeral 5 indicates a valve body provided with a fluid course 6,

terminating at its upper end in a horizontal portion 7 having an outlet 8. The body is provided with two spaced flanges, 9 and 10, respectively, one being fixed to the body and the other being screw threaded on the body, as at 11. Said flanges serve the usual purpose of securing the body to the bottom wall 12, of the flush tank 14. Thus the body may be disposed so that its lower portion is external to the tank, while the upper portion is internal.

The fluid course is intersected by a horizontal bore 15 entering the fluid course at an angle. Just above the point of intersection of the bore 15 with the fluid course, there is provided a suitable seat 16. The fluid course, in the present embodiment, terminates at the lower end in a slightly reduced bore 6^a, which is closed at the lower end by a cap 17.

In conformity with a salient feature of the invention, I provide a valve 18, having an upper cylindrical portion 18^a, a similar lower portion 18^b, and an intermediate portion 18^c, the latter being of reduced diameter. The portion 18^a is provided with an inserted washer 19 adapted to seat on the valve seat. The lower portion 18^b is a close working fit in the bore 6^a, so that said bore and portion 18^b of the piston coat to provide a dash-pot effect for the valve 18. The said portions of the valve should be so disposed that when the valve is seated, the portion 18^c, of reduced diameter is aligned with the horizontal bore 15, while the lower portion of the valve is still within the bore 6^a.

It will be apparent now that when the valve is unseated, as shown in Fig. 3, water rushing around the upper portion of the valve, and through the seat, will have a tendency to force the valve to its seat, and will constantly urge said valve toward its seat. The valve is provided with a stem rising through the bore and passing out of the top of the body through a tubular extension or guide 20.

In this embodiment, a float 21 is employed which is fixed to a float lever 22; the lever being pivoted on the valve body, as at 23, to a fulcrum member 24, such construction being common to flush tank valves.

In conformity with another salient feature of my invention, the upper end of the stem is attached by a pin 25^a, for example, to a slotted yoke 26. The slot 26^a of the yoke is enclosed at both ends and the float lever is

provided with a section 22^a which passes loosely through the yoke. Said section 22^a is provided with an upper arched surface 27, which has a bearing on the upper margin 26^b, of the slot. A similar lower surface 28 may bear on the lower margin 26^c of the slot. The slot is of such length that lost motion is provided between the float lever and the valve stem, or in other words, either 10 the valve stem, or the float lever, may move an appreciable distance without corresponding movement on the part of the other.

It will be understood that the usual flush tank mechanisms include a valve controlled 15 outlet opening (not shown) for draining the tank quickly, as well as other well known parts not needing description or illustration herein.

In considering the operation of the flush 20 tank mechanism as a whole, it will be understood that when the tank is suddenly emptied for flushing purposes, the float descends and moves the valve 18 down to the unseated position in which it is shown in Fig. 3. In 25 such position it allows water to enter through the fluid course and refill the tank, during which operation the float gradually rises. Incoming fluid rushes over the top of the valve and through the fluid course. The 30 fluid pressure below and above the valve will equalize and the valve will remain in open position while the float is rising. In fact, the valve, during this interval, acts similar to any balanced pressure valve.

35 As the float lever moves toward horizontal position, the part of the lever which is within the slotted yoke moves toward the upper margin of the slot, while the balanced pressure on respective ends of the valve allows 40 the valve to remain motionless. Finally the float lever reaches the upper margin of the slot in the yoke and continued movement results in the valve being raised toward its seat. When the valve nears the seat, the action 45 of the water rushing through the seat impels the valve quite forcibly toward its seat. The dash-pot effect of the lower end of the piston prevents very sudden movement of the valve toward its seat but slowly 50 permits such movement. When the valve is quite close to the seat, the force of the water rushing through the restricted space around the upper part of the valve suddenly overcomes the retarding effect of the dash-pot 55 and the valve snaps into closed position causing the slotted yoke to rise independently of the corresponding portion of the float lever. Thus the valve closes almost instantaneously. Since there is no positive connection 60 at this time between the float lever and the valve, there is no tendency on the part

of the float lever or attached parts to reopen the valve. As a consequence, the valve is not only allowed to close quickly, but is allowed to remain closed, and is held so by 65 the pressure of the water which is below the valve, and which would have to be displaced before the valve could descend. Therefore, chattering of the valve is prevented and the objectionable noises common to ordinary 70 float controlled valves, is overcome. When the tank is again emptied at a later time, the water level may drop more rapidly than the float can follow, because the lower end of the valve must displace any fluid which is 75 below it in the dash-pot. By the time the effective weight of the float has become sufficient to open the valve against the fluid pressure which holds it seated, the float is slightly, if at all, buoyed up by the water 80 in the tank. As a consequence, the valve is free to open rapidly, and to move a considerable distance without interference on the part of the float. Were it not for the fact that the dash-pot delays lowering of the 85 float, and the slotted yoke provides lost motion, the valve would immediately open when the float begins descent, and the first inrush of water would send the valve back to its seat, resulting in unsteady action.

90 It will be apparent now that I have provided simple and efficient means in float controlled valves for preventing unsteady action and chattering, and for insuring positive opening and closing of the valve, and 95 while I have shown and described a specific embodiment of my invention, I do not limit myself to any specific construction and arrangement of parts, and may alter the construction and arrangement of parts as I desire, or as occasion requires, without enlarging the scope of my invention as set forth in the appended claim.

100 I claim:—

105 In a float actuated valve, a valve body provided with a longitudinal bore, a second bore intersecting said longitudinal bore at an angle; said body providing a valve seat above the intersection of said second bore, a valve member in said longitudinal bore movable to open and closed positions, respectively; comprising a lower cylindrical member closely fitted in said longitudinal bore below 110 said point of intersection, a reduced diameter intermediate portion above said lower cylindrical member, and an upper cylindrical member above the intermediate portion; the lower termination of the upper cylinder being disposed in alignment with said second bore when the valve is moved to closed 115 position.

120 HARRY C. EUSTIS.
